US0D1047548S

(12) **United States Design Patent** (10) **Patent No.:** **US D1,047,548 S**
(45) **Date of Patent:** **** Oct. 22, 2024**

(54) **CHECKOUT STATION**

(71) Applicant: **Walmart Apollo, LLC**, Bentonville, AR (US)

(72) Inventors: **Darrell Whitelaw**, Pacific Palisades, CA (US); **Wei-Meng Chee**, Los Gatos, CA (US); **John C. Crecelius, Jr.**, Springdale, AR (US); **Andrew J. Grignon**, Half Moon Bay, CA (US); **Kristine L. Pachuta**, Malibu, CA (US); **Stephen S. Hadinger**, San Francisco, CA (US); **Michael C. Cervantes**, San Francisco, CA (US); **Jae Y. Lew**, Mill Valley, CA (US); **Brittany N. Leek**, Waterford, MI (US); **William James Yergin**, San Jose, CA (US)

(73) Assignee: **Walmart Apollo, LLC**, Bentonville, AR (US)

(**) Term: **15 Years**

(21) Appl. No.: **29/809,292**

(22) Filed: **Sep. 27, 2021**

(51) **LOC (14) Cl.** **06-03**

(57) **CLAIM**

The ornamental design for a checkout station, as shown and described.

DESCRIPTION

FIG. 1 is a top front perspective view of a checkout station according to our new design;

FIG. 2 is bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The evenly dashed broken lines depict portions of a checkout station and form no part of the claim. The dash-dot broken lines in FIGS. 2 and 4 depict the claim boundary and form no part of the claim.

1 Claim, 6 Drawing Sheets
